CLAIM

The ornamental design for a floor tile as shown and described.

DESCRIPTION

FIG. 1 is a front perspective view of a floor tile, showing our new and original design;

FIG. 2 is another front perspective view thereof;

FIG. 3 is another front perspective view thereof;

FIG. 4 is a rear perspective view thereof;

FIG. 5 is another rear perspective view thereof;

FIG. 6 is a front view thereof;

FIG. 7 is a rear view thereof;

FIG. 8 is a top view thereof;

FIG. 9 is a bottom view thereof;

FIG. 10 is a left-side view thereof;

FIG. 11 is a right-side view thereof;

FIG. 12 is a cross-sectional view, along the line 12-12 depicted in FIG. 3;

FIG. 13 is a cross-sectional view, along the line 13-13 depicted in FIG. 3;

FIG. 14 is a cross-sectional view, along the line 14-14 depicted in FIG. 3; and,

FIG. 15 is a cross-sectional view, along the line 15-15 depicted in FIG. 3.

The broken lines in the drawings depict portions of the floor tile that form no part of the claimed design. The floor tile includes cross-section cut lines in FIG. 3 in dash-dot which form no part of the claimed design.

1 Claim, 15 Drawing Sheets
